US00D626618S

(12) **United States Design Patent**
Peterson et al.

(10) **Patent No.:** US D626,618 S
(45) **Date of Patent:** ** Nov. 2, 2010

(54) **MODULAR ADJUSTABLE TACTICAL FIREARM SYSTEM**

(75) Inventors: **Morris Peterson**, Earlysville, VA (US); **Matthew Peterson**, Crozet, VA (US); **Gary Vance**, Bristol, VA (US); **William McCormick**, Bluff City, TN (US); **Charles Robert Overbey, Jr.**, Deland, FL (US)

(73) Assignee: **Ashbury International Group, Inc.**, Ruckersville, VA (US)

(**) Term: **14 Years**

(21) Appl. No.: **29/340,269**

(22) Filed: **Jul. 15, 2009**

Related U.S. Application Data

(63) Continuation of application No. 12/251,384, filed on Oct. 14, 2008.

(57) CLAIM

The ornamental design for a modular, adjustable tactical firearm system, as shown and described.

DESCRIPTION

FIG. 1 illustrates a perspective, side view of a new design for a modular, adjustable tactical firearm system depicting a modular, extendable folding buttstock; a modular truss-type forend; and a modular lower receiver;

FIG. 2 illustrates a cross-sectional view of a new design for a modular, adjustable tactical firearm system depicting a modular, extendable folding buttstock; a modular truss-type forend; and a modular lower receiver;

FIG. 3 illustrates a cross-sectional view of a new design for a modular, adjustable tactical firearm system depicting a modular, extendable folding buttstock; a modular truss-type forend; and a modular lower receiver;

FIG. 4 illustrates a side view of a new design for a modular, adjustable tactical firearm system depicting a modular, extendable folding buttstock; a modular truss-type forend; and a modular lower receiver;

FIG. 5 illustrates a side view of a new design for a modular, adjustable tactical firearm system depicting a modular, extendable folding buttstock; a modular truss-type forend; and a modular lower receiver;

FIG. 6 illustrates a top view of a new design for a modular, adjustable tactical firearm system depicting a modular, extendable folding buttstock; a modular truss-type forend; and a modular lower receiver;

FIG. 7 illustrates a bottom view of a new design for a modular, adjustable tactical firearm system depicting a modular, extendable folding buttstock; a modular truss-type forend; and a modular lower receiver;

FIG. 8 illustrates a perspective, side view of a new design for a modular, adjustable tactical firearm system depicting a modular, extendable folding buttstock; a modular truss-type forend; and a modular lower receiver; and,

FIG. 9 illustrates a perspective, side view of a new design for a modular, adjustable tactical firearm system depicting a modular, extendable folding buttstock; a modular truss-type forend; and a modular lower receiver.

The broken, dashed lines shown in the various figures depicting embodiments of the invention are included for the purpose of illustrating environment and do not form any part of the claimed design.
